UNITED STATES PATENT OFFICE.

ALBERT B. CLISSON, OF SYRACUSE, NEW YORK, ASSIGNOR TO THE PROSPERITY COMPANY INC., OF SYRACUSE, NEW YORK, A CORPORATION OF NEW YORK.

LAUNDRY-CHECKING DEVICE.

Application filed January 13, 1927. Serial No. 160,987.

This invention relates to laundry checking devices particularly applicable for checking or keeping track of laundry in commercial laundries and particularly the different 5 classes of laundry which belong in one bundle as a family package, and for facilitating the assembling of the different classes of laundry of the bundles or family package as the laundry operations are completed on all the classes 10 and it further has for its object means by which the operator can see at a glance whether or not all the classes of laundry belonging in a particular package have been assembled or whether or not one or more of the classes are 15 missing.

The invention consists in the novel features and in the combinations and constructions hereinafter set forth and claimed.

In describing this invention reference is 20 had to the accompanying drawings in which like characters represent corresponding parts in all the views.

Figure 1 is a perspective view of one form of this checking device.

25 Figure 2 is a view similar to Figure 1, but with a tag provided with means for attachment to a different class of laundry from that shown in Figure 1.

Figure 3 is a side elevation of a tag holder 30 showing the opposite side to that appearing in Figures 1 and 2.

Figures 4 and 5 are respectively a side elevation and a vertical sectional view of a tag having a different key formation from that 35 shown in Figures 1 and 2.

Figures 6 and 7 are views similar to Figures 4 and 5 of a tag holder having another key formation.

Figures 8 and 9 are respectively an elevation 40 and a sectional view of the tag for the tag holder shown in Figures 4 and 5.

Figure 10 is an elevation of the tag for use with a tag holder shown in Figures 6 and 7.

In checking laundry in commercial laundries many forms of checking devices have 45 been used. One form consists generally of a piece of canvas with a number thereon, one piece of canvas being assigned to each bundle as a family package of laundry. To each 50 piece of canvas, tags are attached as by pins, each tag bearing a similar number to that of the canvas. When the family bundle is sorted out for the different operations the tags are unpinned from the canvas and pinned onto

the different classes of laundry in the package. 55 For example one tag may be pinned to or go along with socks and stockings, another one with table linens, another with shirts, and another with the flat work etc. The piece of canvas itself usually goes along with the 60 flat work or the classification of the bundle which bulks the largest. Like classes of all bundles or packages are bulked together during the washing operations and their identities kept by the tags. After the various 65 classes have gone through the various laundrying operations they are assembled together according to the numbers of their tags and of the piece of canvas and the finished laundry bundled up and delivered. Now the 70 operator with this piece of canvas has no way of knowing accurately whether all of the classes have been assembled. Various modifications of this piece of canvas system have been used. Other systems involving tags 75 having key slots which must fit a fixed key of a compartment, shelf, table or other fixed locality have been used.

This checking device comprises a tag holder in the form of a split ring having its ends 80 or at least one end at one side of the split in the form of a key, and a plurality of tags, each having a key slot conforming to the key formation of the ring and being placeable on and removable from the ring at the split in the 85 ring. This ring corresponds to the piece of canvas of one of the old systems heretofore used and is of such size that it may be, if desired, put in with the main bundle in the washing machine. The ring is also formed 90 with means to indicate to the operator at a glance whether all the tags are assembled thereon. The ring may be flexible but is preferably rigid, and also although it is preferably annular may be of any other shape in 95 so far as it is contiguous with its ends adjacent each other. For instance these rings may be circular as shown or oblong, triangular or any other convenient form.

In the illustrated embodiment of my invention, the tag holders comprise a discoidal body or web encircled by an annular ring, the tag holder being formed with a radial slot extending inwardly from its outer edge splitting the ring and extending far enough into 105 the web to permit a tag with a key slot therein to be slid onto the ring after being passed onto the slot. The rings of the various tag

holders are formed of various cross section particularly at their ends or at one end of each adjacent the slot.

1 designates the tag holder and 2 the ring which encircles the discoidal body or web 3.

4 is the slot cutting the ring 2 and extending to the web 3.

- 5 is a closure in the form of a flat spring secured at one end as 6 to the body of the tag holder and having its free end normally extending into the slot to obstruct it against the entrance of or removal of the tag, and being movable laterally out of position by the tag when moved into the slot and moved out of the slot, it requiring some force to move the spring out of its normal position. This closure or spring is for the purpose of preventing the tags from becoming unintentionally displaced from the tag holder.
- 7 designates the tags formed with key slots 8 conforming to the key formation of the ring 2. These tags are provided with various forms of fastening means and as here shown in Figure 1 the tag is formed with a pin 9 for attaching it to the laundry and in Figure 2 another tag is formed with a cord 9^a by which it is attached to a bundle of laundry. Each tag holder has its individual number and all the tags belonging to any one tag holder have the same number as the tag holder and one tag holder is assigned to each package or family package of laundry and some or all of the tags attached to the various classifications of the laundry of a package. A laundry may have hundreds of tag holders numbered consecutively and each holder a dozen or more tags. Preferably it is more economical from a manufacturing view point to make the rings of key form throughout their length or extent. In Figure 1 the ring 2 is T shaped in cross section and the key slots 8 in the tags 7 are T shaped.

In Figures 4 and 5 the ring 10 is formed of such cross section particularly at its end as to receive only the keys 11 shown in Figures 8 and 9, and in Figures 6 and 7, the ring 12 is of such cross section as to receive tags 13 with the key slots shown in Figure 10.

By my invention while the different bundles of laundry are going through the laundering operations these tag holders may be placed in a pile anywhere or may be passed through with one of the classifications of the laundry and when the laundering is completed all the different classifications of any one package are brought together and if all the tags that belong for instance to tag holder No. 100 are not assembled on tag holder 100, the operator knows that a classification or classifications are missing.

In order that the operator may tell at a glance whether or not all the keys with their classifications have been collected, the tag holder is formed with graduations 14 or other indicating means and if, when the tags are

replaced on the tag holder the space is completely filled between the graduations the operator knows that all the classifications have been collected. He can see at a glance whether or not any tags are missing and if they are he searches for the classification having the missing tag.

What I claim is:

1. A laundry checking device comprising a tag holder in the form of a split ring, the ring adjacent the split being key-form in cross section and tags having key slots conforming with the key formation of the ring. 75

2. A laundry checking device comprising a tag holder in the form of a substantially rigid split ring having one end thereof adjacent the split in the form of a key and a plurality of tags having key slots conforming to the key formation of the ring. 80

3. A laundry checking device comprising a tag holder consisting of a body having a rigid ring portion formed with a radial slot whereby the ring is split with the ends thereof on opposite sides of the slot spaced apart, one end of the ring adjacent the slot being in the form of a key in cross section, a movable closure carried by the body normally closing the slot, and a plurality of tags having key slots conforming to the key formation of the end of the ring, and movable onto and off of the ring through said slot. 90

4. A laundry checking device comprising a tag holder consisting of a body having a rigid ring portion formed with a radial slot whereby the ring is split with the ends thereof on opposite sides of the slot spaced apart, one end of the ring portion adjacent the slot being in the form of a key in cross section, a movable closure carried by the body and normally closing the slot and a plurality of tags having key slots conforming to the key formation of the end of the ring, and movable onto and off of the ring through said slot, the closure being in the form of a laterally movable spring pressed tongue normally arranged to obstruct the slot. 100

5. A laundry checking device comprising a tag holder having a discoidal body and a ring shaped rim around the body, the holder being formed with a radial slot cutting the rim, a spring closure carried by the body and normally projecting into the slot to obstruct it, the end of the ring adjacent the slot being in the form of a key and a plurality of tags having key slots conforming to the key formation of the ring. 115

6. A laundry checking device comprising a tag holder in the form of a substantially rigid split ring having one end thereof adjacent the split in the form of a key and a plurality of tags having key slots conforming to the key formation of the ring, and means on the tag holder to indicate when all the tags belonging to said ring are on the ring. 125

7. A laundry checking device comprising a tag holder having a discoidal body and a ring shaped rim around the body, the holder being formed with a radial slot cutting the rim a spring closure carried by the body and normally projecting into the slot to obstruct it, the end of the ring adjacent the slot being in the form of a key and a plurality of tags having key slots conforming to the key formation of the ring, and means on the tag holder to indicate when all the tags belonging on said tag holder are on the same.
- In testimony whereof, I have hereunto signed my name, at Syracuse, in the county of Onondaga, and State of New York, this 21st day of December, 1926.

ALBERT B. CLISSON.
